Primary Examiner — Lilyana Bekic*(74) Attorney, Agent, or Firm* — Jones Day(57) **CLAIM**

The ornamental design for a liquid reservoir for a nebulizer, as shown and described.

DESCRIPTION

FIG. 1 is a perspective view of a liquid reservoir for a nebulizer showing my design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings depict portions of the liquid reservoir for a nebulizer that form no part of the claimed design.
